UNITED STATES PATENT OFFICE

2,133,566

WRINGER

Julian L. Perkins, West Springfield, Mass.

Application October 6, 1933, Serial No. 692,481
Renewed March 11, 1936

26 Claims. (Cl. 68—253)

This invention relates to improvements in washing machine apparatus and is directed more particularly to improvements in wringers.

- One object of the invention is the provision of a wringer which may be driven from a washing machine motor drive in combination with means for automatically cutting off current to the motor so that an operator may easily and readily stop the wringer to obviate injury.
- Another object of the invention is the provision of a wringer which has associated therewith means adapted for movements between operative and inoperative positions and motor control means associated with the said movable means so that current to the motor may be cut off while the movable means is in operative position whereby an operator may instantly cause the motor to be stopped and thus obviate injury.
- A further object of the invention is the provision of a wringer having co-acting rolls, one of which has a member associated therewith for releasably locking the roll in an operative position and motor control means associated with the member which is conveniently located so that an operator may instantly stop the driving motor and simultaneously release the rolls from operative position.

A further object of the invention is the provision of a wringer having a guard member and associated roll adapted to be releasably connected to a frame in which is a roll. The guard is adapted to swing between a neutral inoperative position and operative positions at either side thereof in which operative positions the guard is releasably locked.

A still further object of the invention resides in the provision of means for rotating the rolls of the wringer in opposite directions so that the feeding-in side of the wringer may be at either side thereof in combination with novel means to control the locking of the guard and its associated roll to the frame in a position at the feeding-in side of the wringer at all times. In that way, the guard is in the path of the arms of the operator of the wringer at all times when in operation whereby the operator may readily and easily engage the same to swing the guard to an inoperative and thereby release the same guard.

Further and various objects and advantages of the invention will be hereinafter more fully referred to in connection with the accompanying description of the present preferred form there-

of, which for purposes of disclosure is shown in the accompanying drawings wherein:

Fig. 1 is a side elevational view of a washing machine apparatus having the novel wringer apparatus of the invention associated therewith. 5

Fig. 2 is a longitudinal elevational and sectional view showing a wringer having certain features of the invention associated therewith, and

Fig. 3 is a transverse sectional view on the line 3—3 of Fig. 2 to show certain features of construction. 10

Referring now to the drawings more in detail the invention will be fully described.

In Fig. 1 a washing machine is shown which has the usual tub 2 supported as by legs 4. A 15 motor M is in some suitable manner associated with the washing machine and, as is ordinary practice, operates a paddle or other agitating mechanism within the tub as well as operates the wringer.

A column 8, associated with the machine, has a shaft therein that is driven from the motor. A gear mechanism, usually referred to as a head and indicated at H, is carried by the column 8 and a wringer structure W is associated with the 25 head.

The head H includes a casing 12 having a driven shaft 14 rotatable therein. A pair of driven gears 16 are slidable, but non-rotatable, on the shaft 14 so as to be shiftable back and forth. In this way one or the other of the gears may be brought into meshing engagement with a driving pinion 18 on the upper end of the shaft 10. With the shaft 10 rotating in one direction it is possible by shifting the gears 16 to rotate 35 the shaft 14 in one direction or the other.

The head may take various forms and may be like that shown in United States Letters Patent 1,875,487 of September 6, 1932, issued to Julian L. Perkins (the applicant) et al.

A lever 20 for shifting the gears works in a slot 22. This is movable back and forth so as to shift the gears 16 back and forth after the manner clearly described in the aforementioned patent.

The wringer W has end frames 24 tied in 45 spaced relation by a rod or tube 20', and the left-hand frame is secured to the casing 12. Bearing blocks 26 are located in slots 28 of the frames and rotatably support a shaft 30 of a lower roll 32 which in this case may be called 50 a drive roll.

The end of the shaft 30 may be connected to the shaft 14 by a coupling or the like but as shown a key 34 is provided for operatively connecting the shafts 14 and 30 so that the latter 55

is driven by the former. Receivers indicated generally by 48 are slideable up and down in the end frames 24. These receivers have ears 42 (see Fig. 3) through which pass bolts 44 which 5 bolts are slideable in bosses 46 of the end frames.

Chambers 48 are provided around the bolts below the bosses 46 and springs 50 surround the bolts. These are under tension between the parts 46 and heads 52 on the lower ends of the 10 bolts. The springs are so arranged as to yieldingly pull the receivers downwardly so that when the wringer rolls are in operable relation the upper roll is under tension as will appear.

The receivers on their adjacent inner faces 15 are provided with guard-receiving slots 52 extending up and down in a vertical relation and intermediate the ends of the slots there are provided recesses 54 such as shown in Fig. 3.

A roll guard assembly similar to that in my 20 United States Letters Patent No. 1,906,406 consists of a guard or swingable upper frame or upper swingable frame part member 60 which has spaced end portions 62. Hubs 64 are provided on the lower end of the guard portions 62 25 and these carry a shaft 66 of an upper roll 33. The shaft 66 and roll 33 may be integral with the shaft rotatable in the hubs or the shaft may be secured to a hub as by a set screw 65, with the roll 33 rotatable on the shaft 66.

30 A projection 68 is provided preferably on each end of the upper frame member and in the form of the invention shown this is a roll rotatable on a pin 70 carried by the upper frame member. The upper frame member is in the shape of a 35 ball for ease in manipulation so that the frame member and roll may be removed from the receivers or dropped thereinto as may be desired.

The slots 52 are so arranged that the hubs 64 of the upper frame member are received therein 40 whereby the roll 33 may be lowered onto the roll 32 therebelow with the frame member in an upright, neutral and inoperative position.

In order to releasably lock the upper frame member and its roll in operative position the 45 frame member is tilted from its central, neutral, inoperative position to one side or the other. As shown in Fig. 3 when the upper roll rests on the lower one the hubs of the upper frame member are disposed in the lower ends of the receiver slots 52 to permit swinging of the frame member 50 which when swung will cause the projection 68 to be carried into one recess 54 or the other of the receivers. The recesses are so arranged as to releasably lock the upper frame member in a 55 tilted operative position as shown in Fig. 3. In this position and by reason of the camming action brought about by swinging of the upper frame member the receivers are elevated slightly against the action of the springs 50 whereby the frame member is releasably locked in the receivers under the influence of the springs.

60 A circuit control switch 70 is associated with the upper frame member 60 which may be of usual form and has a swinging operating lever member 72. Preferably the switch will be arranged so that it is in non-circuit closing position when the member 72 is in a lower position as shown in Fig. 2. When the member 72 is swung upwardly the switch will be in circuit-closing position.

70 A cable 74 extends from the switch 70 to a plug 76 provided with prongs 78 receivable in a receptacle 80 fixed in a member 82 associated with one of the wringer end frames. The plug 76 and receptacle 80 are so arranged that when

the upper frame member is moved upwardly from the receivers the plug will be pulled from the receptacle and disconnect the same. A cable 84 extends from the receptacle to the motor M and by disconnecting the receptacle and plug the 5 circuit to the motor is disconnected. A manually engageable grip bar 90 has a pin 92 slideable in the upper frame member and a rod 94 also slideable in the frame member is provided with an opening 96 which receives the lever 72 of the 10 switch. As the grip 90 and rod 94 are moved towards and away from the upper frame member the lever of the switch 72 is swung up and down or back and forth to make or break a circuit. 15

A lock member 106 is pivoted at 102 to the upper frame member and has a slot 104 at one end which receives a pin 107 of a rod 108 fixed to the grip 90. As the member 90 is moved towards and away from the frame member the 20 lock member 106 is moved up and down. Slots 110' are provided in the receivers at the upper sides thereof and at either side of the central slots 52. The slots 110' are arranged to receive an end latch portion 112 of the lock member 106. 25

Cap members 114 are pivoted as at 115 to the receivers and they may swing from the position shown in Fig. 3 where they overlie the receivers and the slot thereof to a position at one side thereof. The caps are swingable as the upper 30 frame member is withdrawn from the receivers and when in an open position permit the frame member to be dropped into the receivers.

The operation of the apparatus will now be 35 described in detail.

As shown in Fig. 2 the upper frame member 60 and upper roll 30 are in a neutral, vertical and inoperative position with the operating member 90 in its depressed position nearest the upper frame member. In this position the lock 40 member has its end portion 112 above the upper ends or sides of the receivers, and from this position the upper frame member may be swung in one direction or the other.

It will be assumed that the plug 76 is in the 45 receptacle 80 so as to connect the motor M to the switch 70 which is in off position. The gears 66 are positioned so that the roll 32 is operated in the desired direction.

The upper frame member is swung from the 50 neutral, vertical and inoperative position mentioned to a tilted operative position such as shown in Fig. 3. The upper frame member is releasably locked to the receivers in this operative position by means of the hubs and projections in the slots 55 and recesses thereof as has been described. As the member 90 is moved upwardly away from the upper frame member and when the upper frame member is in this tilted operative position the lock 106 is swung so that its part 112 enters a 60 slot 110'. In this way the upper frame member is releasably held against swinging to a neutral, inoperative position. As the member 90 is pulled upwardly into an operative position, the arm or lever 72 of the switch device is moved to close the 65 circuit including the switch and the motor M, whereupon the motor is set in operation and the lower roll 32 is driven thereby through the gears described.

During the wringing operation the upper roll 70 yields to accommodate material being passed between the rolls. Should it be necessary and desirable however to instantly stop the wringer the operator has but to strike the member 90 lightly to thereby depress it and shift lever 72 of the 75

switch and cut off the current. This movement of the member 90 swings the lock member downwardly so that its outer end 112 is removed from the slot.

- 5 Thus, simultaneously with striking the member 90, the operator may swing the upper frame member to its neutral, operative position and release the frame member from the receivers. It is not only possible therefor to instantly cut off the 10 current to the motor driving the wringer but release the upper frame member as well. Should an operator have a hand or other part caught between the rolls he is safeguarded against injury by striking the grip 90 and at the same time 15 swinging the frame member.

When the upper frame member is swung to neutral position and it is desired to remove the same from the wringer it may be done by simply raising the frame member and simultaneously with 20 this rising movement the plug 76 is withdrawn from the receptacle 80 to break the motor line.

It will be noted that the upper frame member when in the receivers may be swung in either or opposite directions from the central inoperative 25 position. It is desired that the frame member when in operative position be at the leading-in side of the rolls. For instance, with the lower roll rotating clockwise and the upper roll rotating counter-clockwise, the leading-in side is at the 30 left. The operator will ordinarily be positioned on this leading-in side so it is desired that the upper frame member be nearest the operator and within easy reach.

Means is provided to prevent the upper frame 35 member being swung from inoperative to operative position away from the leading-in side and away from the operator to insure that the upper frame member is readily accessible. This includes a control member 110 associated with the 40 shaft 30 which frictionally embraces the shaft. This is accomplished by splitting the hub 112 of the member as at 114.

With the leading-in side of the rolls at the left, as shown in Fig. 3, the shaft 30 rotates clockwise 45 and swings the member 110 to the right against some stationary part such as the side of the slot 52 of the receiver. In this position the upper end 116 of the member is in front of the recesses 54 at the right of the receiver whereby the projection 50 68 of the upper frame member cannot seat in the receiver recesses at the right. To lock the frame member it must be swung away from the member 110 to the leading-in side of the wringer at the left thereof. The shaft 30 slips in the member 110 55 and frictionally urges it towards the side of the slot.

When the shaft 30 is rotated counter-clockwise so as to bring the leading-in side at the right of the wringer the member 110 is swung to the left side of the receiver and the upper frame member can only be swung to the leading-in side or to the right. This insures that the frame member when 60 in operative position is at the leading-in side and the side of the wringer at which the operator will 65 stand.

While I have described my invention in great detail and with respect to preferred embodiments thereof, I do not desire to be limited to such detail or embodiments since many changes or modifications may be made without departing from the spirit and scope of the invention in its broader aspects. What I desire to claim as new and secure by Letters Patent of the United States is:

1. A wringer apparatus comprising in combination, a lower frame having receiving means for

an upper frame, a separate upper frame, rolls on both of said frames, electrical driving means for said rolls, the upper frame having a manually engageable part, means to releasably lock the upper frame in the lower frame with the rolls operatively related, a switch for said driving means on said manually engageable part and means for simultaneously operating said switch and releasable locking means. 5

2. A wringer apparatus comprising in combination, a frame having a roll therein, an upper frame unit having a second roll therein, electrical driving means for said rolls, receivers on said frame, the said receivers and unit being provided with means to permit said unit to swing between 10 operative and inoperative positions and to releasably lock the unit in operative position with the rolls in operative contact, and a switch for a motor circuit for said driving means on said unit having an actuating member movable between operative and inoperative positions, all adapted and arranged whereby the unit and actuating member may be moved simultaneously between operative and inoperative positions. 20

3. A wringer apparatus comprising in combination, a frame having a roll therein, an upper frame unit having a second roll therein, electrical driving means for said rolls, receivers on said frame, the said receivers and unit being provided with means to permit said unit to swing between 25 operative and inoperative positions and to releasably lock the unit in operative position with the rolls in operative contact, a switch for a motor circuit for said driving means on said unit having an actuating member movable between operative and inoperative positions, and separable connections for a circuit including said switch and motor associated with said frame and unit disengageable as the unit is removed from the 30 frame, all adapted and arranged whereby the unit 35 and actuating member may be moved simultaneously between operative and inoperative positions. 40

4. A wringer apparatus comprising in combination, a frame having a roll therein, an upper 45 roll unit having a second roll therein, electrical driving means for said rolls, receivers on said frame, the said receivers and unit being provided with means to permit said unit to swing from an inoperative to an operative position with the rolls 50 in operative contact, a switch for said driving means on said unit having an actuating member movable between operative and inoperative positions, and means to releasably hold the unit in 55 operative position operable by said actuating member whereby the unit and switch may be operated simultaneously.

5. A wringer apparatus comprising in combination, a frame having a roll therein, an upper roll unit having a second roll therein, electrical driving means for said rolls, receivers on said frame, the said receivers and unit being provided with means to permit said unit to swing between operative and non-operative positions with the rolls in operative contact, a switch for said driving 65 means on said unit having an actuating member movable between operative and inoperative positions, means to releasably hold the unit in operative position operable by said actuating member as it is moved to inoperative position, means 70 to hold said actuating member against movement from inoperative position to operative when the unit is in inoperative position.

6. A wringer apparatus comprising in combination, a frame having a roll therein, electrical 75

driving means for said rolls, receivers associated with the frame, an upper frame unit including a roll therein, means associated with said unit and receivers to facilitate swinging movements of the unit between operative and inoperative positions, a switch device on said unit for said driving means including a manually operable actuating member movable between operative and inoperative positions, means to releasably lock said unit in operative position and connections between said means and said actuating member arranged and adapted whereby the unit is released by the member when said member is operated to actuate said switch.

15. 7. A wringer apparatus comprising in combination, a frame having a roll therein, electrical driving means for said rolls, receivers on said frame, an upper frame unit receivable in the receivers including a roll, means associated with said unit and receivers to facilitate swinging movements of said unit between operative and inoperative positions and to releasably lock said unit in operative position, a switch device for said driving means on said unit including a manually operable actuating member, holding means to hold said unit in operative position, and connections between said means and actuating member whereby the holding means is released by the operation of the actuating member to facilitate swinging of the unit to inoperative position.

8. A wringer apparatus comprising in combination, a lower frame having a rotatable roll and receiving means, an upper frame having a manually engageable part, a roll in said frame, releasable locking means associated with the receiving means and frame for releasably locking the upper frame to the receiving means with the manually engageable part thereof at either side of the wringer, means for driving one of said rolls in opposite directions so the feeding-in side of said rolls may be at either side of said wringer, and control means to permit locking of the upper frame to the receiving means only when the manually engageable part thereof is disposed at a side of the wringer corresponding to the feeding-in side of the rolls.

9. A wringer apparatus comprising in combination, a lower frame having a rotatable roll and receiving means, an upper frame having a manually engageable part, a roll in said frame, releasable locking means associated with the receiving means and upper frame for releasably locking the upper frame to the receiving means with the manually engageable part thereof at either side of the wringer, means for driving one of said rolls in opposite directions so the feeding-in side of said rolls may be at either side of said wringer, and control means to permit locking of the upper frame to the receiving means with the manually engageable part thereof disposed only at a side of the wringer corresponding to the feeding-in side of the rolls, the control means being shiftable between two positions and its position controlled by the direction of rotation of said rolls.

10. A wringer apparatus comprising in combination, a lower frame having a rotatable roll and receiving means, an upper frame having a manually engageable part, a roll in said frame, releasable locking means associated with the receiving means and upper frame for releasably locking the said frame to the receiving means with the manually engageable part thereof at either side of the wringer, means for driving one of said rolls in opposite directions so the feeding-in side of said rolls may be at either side of said wringer,

and control means to permit locking of the upper frame to the receiving means with the manually engageable part thereof disposed only at a side of the wringer corresponding to the feeding-in side of the rolls, the control means being shiftable between two positions and actuated between said positions by rotation of one of said rolls.

11. A wringer apparatus comprising in combination, a lower frame having a rotatable roll and receiving means, an upper frame having a manually engageable part, a roll in said upper frame, releasable locking means associated with the receiving means and upper frame for releasably locking the said frame to the receiving means with the manually engageable part thereof at either side of the wringer, means for driving one of said rolls in opposite directions so the feeding-in side of said rolls may be at either side of said wringer, and control means to permit locking of the upper frame to the receiving means with the manually engageable part thereof disposed only at a side of the wringer corresponding to the feeding-in side of the rolls, the control means being shiftable between two positions and moved between said positions accordingly as the rolls are rotated in one direction or the other.

12. A wringer apparatus comprising in combination, a lower frame having a rotatable roll and receiving means, an upper frame having a manually engageable part, a roll in said frame, locking means associated with the receiving means and upper frame for releasably locking the said frame to the receiving means with the manually engageable part thereof at either side of the wringer, means for driving one of said rolls in opposite directions so the feeding-in side of said rolls may be at either side of said wringer, and control means to permit locking of the upper frame to the receiving means only when the manually engageable part thereof is disposed at a side of the wringer which corresponds to the feeding-in side of the rolls, the said control means including a part frictionally engaged by one of said rolls and movable thereby between control positions accordingly as the direction of said roll is changed.

13. A wringer apparatus comprising in combination, a lower frame having a rotatable roll and receiving means, an upper frame having a manually engageable part, a roll in said upper frame, locking means associated with the receiving means and upper frame for releasably locking the upper frame to the receiving means with the manually engageable part thereof at either side of the wringer, means including a shiftable part for driving one of said rolls in opposite directions so the feeding-in side of said rolls may be at either side of said wringer, and control means to permit locking of the upper frame to the receiving means only when the manually engageable part thereof is disposed at a side of the wringer which corresponds to the feeding-in side of the rolls, the said receiving means including slots for receiving opposite ends of the upper frame and the said control means including a part associated with one of said slots and movable by rotation of one of said rolls.

14. A wringer apparatus comprising in combination, a lower frame having a rotatable roll and receiving means, an upper frame having a manually engageable part, a roll in said upper frame, locking means associated with the receiving means and upper frame for releasably locking the said frame to the receiving means with the manually engageable part thereof at either

- side of the wringer, means including a shiftable part for driving one of said rolls in opposite directions so the feeding-in side of said rolls may be at either side of said wringer, and control means 5 to permit locking of the upper frame to the receiving means only when the manually engageable part thereof is disposed at a side of the wringer which corresponds to the feeding-in side of the rolls, the said receiving means including 10 slots for receiving opposite ends of the upper frame and the said control means including a part movable relative to one of said slots and being movable by rotation of one of said rolls between positions at opposite sides of said slots.
- 15 15. A wringer apparatus comprising in combination, a lower frame having a rotatable roll and receiving means, an upper frame having a manually engageable part, a roll in said upper frame, locking means associated with the receiving means and upper frame for releasably locking the said upper frame to the receiving means with the manually engageable part thereof at either side of the wringer, means including a shiftable part for driving one of said rolls in opposite directions so the feeding-in side of said rolls may be at either side of said wringer, and control means to permit locking of the upper frame to the receiving means only when the manually engageable part thereof is disposed at 20 a side of the wringer which corresponds to the feeding-in side of the rolls, the said receiving means including slots for receiving opposite ends of the upper frame arranged to permit swinging movements thereof between a neutral inoperative 25 and operative positions and the said control means including a part associated with one of said slots which is movable transversely thereof to permit the upper frame to swing in one direction only.
16. A wringer apparatus comprising in combination, a lower frame having a rotatable roll and receiving means, an upper frame having a manually engageable part, a roll in said upper frame, locking means associated with the receiving means and upper frame for releasably locking the said frame to the receiving means with the manually engageable part thereof at either side of the wringer, means including a shiftable part for driving one of said rolls in opposite directions so the feeding-in side of said rolls may be at 30 either side of said wringer, and control means to permit locking of the upper frame to the receiving means only when the manually engageable part thereof is disposed at a side of the wringer which corresponds to the feeding-in side of the rolls, the control means being frictionally engaged by one of said rolls and movable thereby between control positions.
- 35 17. A wringer apparatus comprising in combination, a frame, an upper frame swingable between an inoperative position and operative positions at either side of the wringer, co-operating rolls, control means actuated by one of said rolls to limit movement of the upper frame from inoperative to an operative position at a side of the wringer corresponding to the leading-in side of the rolls.
- 40 18. A wringer apparatus comprising in combination, a frame, an upper frame movable between operative positions at either side of the wringer, co-operating rolls, means for driving said rolls in opposite directions whereby the leading-in side of the rolls is at either side of the wringer and control means to limit movement of the upper frame to that side only of the wringer which is 45 the leading-in side of the rolls.
- 45 19. A wringer apparatus comprising in combination, a frame, an upper frame movable between operative positions at opposite sides of the wringer, co-operating rolls, driving means for driving said rolls in opposite directions to bring the leading-in side of the rolls at either side of the wringer, and control means operable by said driving means to limit movement of the upper frame to that side of the wringer which is the leading-in side of the rolls.
- 50 20. The combination in a wringer of a pair of rolls, a frame structure therefor including releasable pressure means for holding said rolls together under tension, a manually engageable longitudinally extending operating member pivoted on said frame for swinging movements from operative positions at either side of the uppermost roll of the pair to an inoperative position thereabove and including means to release said pressure means, releasable locking means for locking said operating member in operative position, and a grip for actuating said locking means on said operating member.
- 55 21. The combination in a wringer of a pair of rolls, a frame structure therefor including releasable pressure means for holding said rolls together under pressure, a manually engageable member pivoted on said frame on an axis substantially parallel to the axes of the rolls for swinging movements from operative to inoperative positions and including means to release said pressure means, releasable locking means for locking said operating member in operative position, and a grip movable on said operating member connected to and adapted to release said locking means.
- 60 22. The combination in a wringer of a pair of rolls, a frame structure therefor including releasable pressure means for said rolls, a manually engageable member pivoted on said frame swingable between operative and inoperative positions and adapted to release said pressure means on swinging movements, and releasable locking means for locking said member in a certain position, the said means including a member movable on said operating member which is engageable with an abutment provided on a part of said frame in relation to which the operating member swings.
- 65 23. The combination in a wringer of a pair of rolls, a frame structure therefor including releasable pressure means for said rolls, a manually engageable member pivoted on said frame and swingable between operative and inoperative positions and adapted to actuate and release said pressure means on swinging movements, releasable locking means for locking said operative member in a certain position, the said means including a member movable on said operating member which is engageable with an abutment provided on a part in relation to which the operating member is swingable, and a grip on said operating member for operating the releasable locking means.
- 70 24. The combination in a wringer of a pair of rolls, a frame structure therefor including releasable pressure means for said rolls, a manually engageable member pivoted on said frame and swingable between operative and inoperative positions and adapted to actuate and release said pressure means on swinging movements, and releasable locking means for locking said operative member in a certain position, the said means including a notch provided in a part with relation to which the operating member swings and a 75

- movable member on said operating member receivable in said notch.
25. The combination in a wringer of a pair of rolls, a frame structure therefor including releasable pressure means for said rolls, a manually engageable member swingable between operative and inoperative positions and adapted to actuate and release said pressure means on swinging movements, releasable locking means for locking said operative member in a certain position, the said means including a notch provided in a part with relation to which the operating member swings and a movable member on said operating member receivable in said notch, and a grip on said operating member for actuating the movable member.
26. A wringer comprising in combination, a frame structure, a longitudinally extending manually engageable operating member mounted there-
- in for swinging movements between a central neutral position and other positions at either side thereof, co-operating rolls associated with the operating member and frame structure, pressure means for said rolls to apply and release pressure thereto, a lock part associated with the frame and movable on the operating member and a part adjacent the said operating member engageable thereby and constituting therewith a lock mechanism, a manually engageable lock actuator on said operating member, and connections between said lock part and actuator, the said pressure applying means operable to apply pressure independently of the lock mechanism and adapted to release pressure as the operating member moves from said other position to neutral position.

JULIAN L. PERKINS.
